UNITED STATES PATENT OFFICE.

HELEN C. EVERTS, OF SUTTON, NEBRASKA.

TABLE.

Application filed March 24, 1927. Serial No. 178,006.

This invention relates to tables and it is primarily an object of the invention to provide a device of this kind especially designed and adapted for use in a sick room.

5 It is also an object of the invention to provide a table of this kind which may be readily and conveniently folded to facilitate transportation or storage and which when in use may be readily positioned over a person lying 10 down and more particularly in bed.

An additional object of the invention is to provide a device of this kind including a top which may be readily positioned for use for eating or the like and which may be also 15 raised or elevated to facilitate its use as a book holder.

The invention consists in the details of construction and in the combination and arrangement of the several parts of my improved table whereby certain important advantages are attained and the device rendered simpler, less expensive and otherwise more convenient and advantageous for use, as will be hereinafter more fully set forth.

25 The novel features of my invention will hereinafter be definitely claimed.

In order that my invention may be the better understood, I will now proceed to describe the same with reference to the accompanying 30 drawing, wherein:—

Figure 1 is a view in perspective illustrating a table constructed in accordance with an embodiment of my invention with the table top in raised or lifted position;

35 Figure 2 is a cross sectional view taken through my improved table as herein disclosed with the top in its lowered position and with an intermediate portion broken away;

40 Figure 3 is a detailed sectional view taken substantially on the line 3—3 of Figure 2;

Figure 4 is a view in perspective of one of the latch structures for holding a supporting leg in either operative or inoperative position.

45 As herein disclosed, my improved table comprises a rectangular frame F having the outer margins of its end members 1 defined by the depending flanges 2. Each of the end members 1 of the frame F is provided adjacent its extremities with the brackets 3 suitably secured to the under surface thereof and which provide pivotal mountings for the inwardly disposed arms 4 carried by the extremities of a supporting member M.

The supporting member M, as herein disclosed, is formed from a single strand of wire of requisite gauge and is formed to provide the supporting legs 5 of desired length. Each of the legs 5 comprises parallel portions 60 *a* and *b* connected at their outer extremities, as at *c*, while the inner extremities of the portions *b* are connected by the cross portion *d*. The portions *a* extend beyond the inner extremities of the portions *b* and are provided 65 with the inwardly disposed arms 4.

The pivoted or inner extremity of a portion *a* of each of the members M extends between two arcuate plates 6 and 7, one of said plates, as 6, being connected, as at 8, to the 70 flange 2 while the second arcuate plate 7 is fastened, as at 9, to a side member 10 of the frame F. The arms 6 and 7 possess a certain degree of inherent resiliency permitting a member M to be readily swung into extended 75 or working position or into folded or inoperative position. These plates 6 and 7 are spaced apart a distance less than the diameter of the portion *a* of a member M but adjacent their extremities are provided with the opposed jaws 11 in which the portion *a* is received when the member M is in either of its two positions to effectively maintain the member M in either of such positions. As herein disclosed, the jaws 11 are provided by pressing the plates 6 and 7 to provide the inwardly 80 facing and opposed beads.

Hingedly connected, as at 12, to the outer marginal portion of a side member 10 is a marginal portion of a table top T. This top 90 T is of such dimensions and configuration to entirely overlie the frame F when in its lowered position. The marginal portions of this top T are defined by an upstanding rim 14 which serves to prevent articles from 95 sliding off.

Pivottally connected, as at 15, with a depending end flange 2 and at the side of the frame F remote from the hinge connections 12 is a rod 16 of desired length and which is 100 adapted to engage the adjacent end marginal portion of the table top T to maintain such table top in desired raised or elevated position as illustrated in Figure 1. To facilitate the functioning of the rod 16 the under surface of the top T is provided with the spaced depressions 17 as indicated by dotted lines in Figure 1.

In practice, with the supporting members M extended, my improved table is adapted to 110

be supported upon a bed at a point preferably over the hips of the patient so that the patient can be conveniently propped up with pillows or by a conventional back rest. If the 5 table is to be used in serving a meal the top T is in its lowered position but if the patient desires to read or write the top T is propped up by the rod 16 at desired angle and thereby affording an effective and convenient support 10 for a book or rest for the paper.

When my improved table is not in use the table top T is dropped down upon the frame F and the supporting members M swung inwardly to underlie the frame. By this adjustment the table may be readily placed between a mattress and spring or otherwise stored away. This compact adjustment of 15 the table also facilitates its transportation.

By using the frame F the weight of the 20 table is materially reduced and, therefore, its convenience in handling is materially increased.

From the foregoing description it is thought to be obvious that a table constructed 25 in accordance with my invention is particularly well adapted for use by reason of the convenience and facility with which it may be assembled and operated, and it will also be obvious that my invention is susceptible 30 of some change and modification without departing from the principles and spirit thereof and for this reason I do not wish to be understood as limiting myself to the precise arrangement and formation of the several parts 35 herein shown in carrying out my invention in practice except as hereinafter claimed.

I claim:—

1. A table structure of the character described, comprising a top frame having a depending flange at and extending throughout the length of each of two opposite edges, a pair of legs at each of said flanged edges, 40

each comprising a substantially U-shaped body having one portion thereof extended and terminating in an angular arm positioned 45 against the under side of the top frame, a bearing carried by the frame for and receiving each of said annular arms, a connecting bar between the other portions of the U-shaped legs of each pair, a keeper member 50 having frictional engagement with the extended portion of each of said U-shaped legs and comprising an arcuate body extending between the inner face of a flange and the adjacent under face of the table top frame. 55

2. A table of the character described, comprising a top frame having a depending flange at and extending throughout the length of each of two opposite edges, a pair of supporting legs adjacent each of said flanges, 60 each of said legs comprising a substantially U-shaped body having one side thereof of greater length than the other and terminating in a right angularly extending portion, a bearing for each of said right angle portions 65 positioned at the under side of the frame, a connecting bar between the adjacent other sides of each pair of legs, forming a unitary structure of each pair, and a keeper associated with each of said legs and comprising a 70 pair of arcuate plate members arranged in spaced relation at opposite sides of the side of greater length, one of said plates being secured at one end to the top frame and the other being secured at the opposite end to the 75 adjacent flange, said plates having resilient frictional engagement with the leg side positioned therebetween and having opposed complimentary recesses at each end to receive the leg side to hold the same in open or closed 80 position.

In testimony whereof I hereunto affix my signature.

HELEN C. EVERTS.
